UNITED STATES PATENT OFFICE.

LOUIS W. G. FLYNT, OF ROCHESTER, NEW YORK, ASSIGNOR TO QUENTIN W. BOOTH AND IRVING E. BOOTH, OF ROCHESTER, NEW YORK.

BURNISHING-MACHINE FOR IMITATION-STITCH IMPRESSIONS OR INDENTATIONS.

No. 845,939.

Specification of Letters Patent.

Patented March 5, 1907.

Application filed November 2, 1904. Serial No. 231,133.

To all whom it may concern:

Be it known that I, LOUIS W. G. FLYNT, a subject of Great Britain, residing at No. 876 Genesee street, Rochester, in the county of 5 Monroe and State of New York, United States, have invented certain new and useful Improvements in Burnishing-Machines for 10 Imitation-Stitch Impressions or Indentations, of which the following is a specification, reference being had therein to the accompanying drawing.

This invention relates to burnishing-machines, and has for its object the provision of a machine of this type which, although susceptible of various uses, is primarily designed 15 for burnishing impression-strokes or imitation-stitch indentations usually bordering the projecting upper surface of the soles of boots and shoes.

20 In the pending application of Olson and Flynt, Serial No. 232,309, filed August 26, 1904, a machine is disclosed for forming these stitch indentations or imitations, and the present machine is especially intended to 25 finish and burnish the impressions after they have been made by such a machine and after the edges of the sole have been inked.

It has been the practice in this art to wheel 30 the edges of boots and shoes before they are inked, and frequently before they are trimmed, and in order that they may present a clean, bright, and uniform appearance it is desirable to go over them with a brush or hand-wheel after the inking has been done. 35 The present invention makes this hand-finishing unnecessary and greatly improves the quality of the work.

Novel and advantageous features of a machine made in accordance with my invention 40 include a burnishing-tool having a rounded outer edge, the same being adapted to be reciprocated in the stitch indentations and the purpose of the rounded ends being to prevent any tendency of the tool to scrape and 45 roughen the stitch impressions, means for maintaining the tool in contact with the indentations during its reciprocation, an adjustable work-support operatively related to the tool, means for adjusting the tool relative to the work-support, and means for throwing the tool into or out of operative engagement with its actuating means. More 50 specifically, the burnishing-tool is composed

of elements whereby it may have a progressive rotary movement and simultaneous reciprocation. 55

The above-stated as well as many other novel features of the invention will be apparent from the detailed description hereinafter when read in connection with the accompanying drawings, forming part hereof, and wherein a convenient embodiment of the invention is illustrated, it being understood that the invention is not limited to the precise embodiment disclosed herein nor to any 65 of the details or arrangements of parts thereof, since others may be resorted to without in the least departing from the spirit of the invention.

In the drawings, Figure 1 is a side elevation of the complete machine. Fig. 2 is a top plan view. Fig. 3 is a vertical section on the line *x* *x* of Fig. 2. Fig. 4 is a vertical section of the upper portion of the machine, taken through the longitudinal axis of the 75 machine or in a plane transverse to that of the preceding figure. Fig. 5 is a bottom view of the work-support shown in Fig. 1. Figs. 6 and 7 are details of the tool, and Fig. 8 is a detail of the cam and plunger roller. 80

Referring more specifically to the drawings, wherein like reference characters refer to corresponding parts in the several views, A designates the frame of the machine, which is provided with two bosses *a* *a'* and lugs or 85 projections *a*², *a*⁴, and *a*⁶. The bosses are fitted with bushings *A*² *A*³, in which is journaled a shaft E.

B is a hollow cylindrical case, from the ends *b* of which project bearings *b*² *b*³, which 90 are bored to receive the bushings before referred to, about which the case is free to pivot. This case is also provided with a projection *b*⁴, the purpose of which will be hereinafter described.

The shaft E is journaled in the bearings or bushings *A*² *A*³, and endwise movement thereof is prevented by a hub *f* of a pulley F, bearing against the end of the bearing *b*² at one end, and the collar G, bearing against the 100 end of the bushing *A*² at the other. The collar G is secured to the shaft by means of a set-screw *g*. At a point about midway between the faces *b* *b* of the casing B the shaft E is milled to form flat faces or cams *e*, four 105 of these being shown, but any desired num-

ber being provided in different machines according to their use. The function of these cams will hereinafter appear.

The projection b^4 projects radially from the cylindrical case B and is bored to receive a plunger H, said plunger being of a reduced diameter at its forward end and fitted to slide freely through a bushing I, threaded into the projection b^4 . The opposite or rear end h of the plunger H is turned to fit the bore of the projection b^4 , and its end is slotted to receive a roller J, the latter being journaled in the plunger H through the medium of a pin j . Resting against the shoulder formed by the enlarged or rear end h of the plunger and encircling the reduced forward portion thereof is a coiled spring K, the other end of the spring resting against the end of the bushing I. The purpose of the spring is to hold the plunger H in a retracted position and force the roller J against the cam-faces of the shaft E.

On the outer end of the plunger H, I provide a burnishing-tool D, which is free to revolve about a pivot d and is prevented from slipping therefrom by a screw d^2 . The burnishing-tool is tapered, being preferably frusto-conical; but its axis d is at an angle to the longitudinal axis of the plunger, whereby the lower or working portion of the burnishing-tool is substantially parallel to said longitudinal axis of the plunger. The burnishing-tool, while free to progress in a rotary direction to present a working surface to each of the stitch impressions or indentations surrounding the sole of the shoe, is simultaneously rapidly reciprocated to burnish said impressions or indentations through the medium of the rotating cams e on the shaft E engaging the roller J on the plunger and forcing the same outwardly in opposition to the quick return motion thereof under the influence of the spring K. Owing to the reciprocating movement imparted to the burnishing-tool it is quite essential that the ends of the flutes b^3 on the tool be beveled or rounded in all directions at the outer ends thereof to prevent the otherwise sharp edges of the tool from scraping or roughening the impressions. This is an important feature attending the present invention, and possibly would not be necessary in machines where the tool is not reciprocated while in engagement with the stitch impressions. In its back-and-forth movement the plunger H is prevented from turning by reason of the side faces of the cam engaging roller J being confined between the inner ends of the bushings A^2 A^3 . The shaft E is rotated through the medium of a belt-pulley F at one end thereof, power being transmitted to said pulley from any suitable source, and it is of course desirable that instrumentalities be afforded whereby 65 the actuation of the burnishing-tool may be

stopped without interfering with the continuous operation of the shaft. To this end a portion of the bush A^2 overlaps the cam portion of the shaft E, the other portion of said bush being cut away to permit the contact of the cam-roller J with the faces of the cams. It is obvious that by rotating the bushing A^2 about the shaft the overlapping portion x^2 thereof will act as a cam, and, riding under the roller J, will force said roller away from contact with the cam portion of the shaft, and so stop the motion of the plunger H normally incident to the rotation of said shaft, Fig. 8. The turning of the bushing A^2 in order to stop the movement of the plunger, as just defined, is conveniently effected by means of an operating-handle S, threaded into a cap R, covering the end of the shaft E and collar G and fitted to the bushing A^2 . The inner end of this handle fits into a complementary hole in the bushing, and owing to this connection when the handle is manipulated said bushing is turned about the shaft E and the cam-roller J allowed to come in contact with the cam portion of said shaft or pushed away from engagement therewith, according to the desire to start or stop the reciprocation of the plunger. Two pins b^5 , projecting from the face of the casing B, limit the movement of the handle S in opposite directions. 95

A spring L tends to hold the casing B down against the head of an adjusting-screw M, threaded into the lug a^3 of the frame A, the tension of said spring being adjusted by a thumb-nut N and eyebolt O, to which the spring is attached. It is also by means of this spring that the burnishing-tool is kept in contact with the stitch impressions or indentations while being rapidly reciprocated therein. A portion of the case B is cut away, as at b^6 , so that the casing B will set over and span the bearings a a^2 of the frame A, the opening provided by the cut-away portion being sufficient to permit the movement of the casing B about the bushings on which it is journaled. 105

A table-supporting rod P is firmly secured in the lug a^4 of the frame A, which is bored to receive it. The outer end of this rod is approximately rectangular in cross-section, and the table (represented at C) is provided with two depending lugs c^2 , adapted to span said rectangular end of the rod, whereby the table may be pivoted thereto by means of a pin c . 115 To lock the table in adjusted positions relative to the burnishing-tool, the end of the rod P is slotted from its outer end inwardly and is provided with a screw Q, threaded through one half of said slotted end and bearing freely against the inner face of the opposite half thereof. Owing to this arrangement the turning of the screw Q inwardly causes the two members of the slotted rod to separate or expand between the two lugs c^2 on the 120 125 130

table, whereby the adjoining surfaces of said members and lugs will impinge with sufficient force to frictionally resist accidental displacement of the work support or table. 5 This adjustable table feature of the invention will not be claimed herein, inasmuch as it more properly constitutes subject-matter for a divisional application.

10 A treadle-rod T, engaging a pin b⁷ on the casing B, provides a means for rotating the casing against the action of the spring L and elevate the burnishing-tool to permit the insertion and withdrawal of the work from between the tool and the work-supporting 15 table. The lower end of the treadle-rod is connected with any suitable floor-treadle.

15 The burnishing-wheel may be heated by gas or other means, a tubular portion b⁸ being cast on the case B for convenience in attaching gas appliances.

20 The operation of the machine may be described as follows: After heating the burnishing-tool and adjusting the same relative to the table by means of the screw M and 25 setting the table at the desired angle to said tool, the shaft E being revolved through the medium of its pulley, the handle S is manipulated, so as to allow the roller J to contact with the cam portions of the shaft. This 30 immediately imparts a high reciprocating movement to the plunger H and burnishing-tool. The burnishing-tool is then raised away from the table by means of the treadle to permit the insertion of the work therebetween. 35 Thereafter the treadle being released, the spring L holds the burnishing-tool in constant engagement with the work and maintains the work upon the table. The pitch and ribs of the tool correspond to 40 the stitch impressions or indentations previously made in the edge of the sole, and by drawing the sole edge under the rapidly-reciprocating burnishing-tool, the movement of the tool being in line with the direction of the impressions, it cleans and burnishes each impression and gives them a very superior finish. The free rotary movement of the tool permits the same to act progressively from stitch to stitch without disengaging the same from the work or in the least impeding its reciprocatory movement as the shoe-sole is passed therebeneath.

45 I am not unmindful of the fact that in some instances the present machine may be employed with slight or no change for both forming the stitch impressions or indentations and burnishing or finishing the same.

50 In these specifications where I have employed the term "wiping" as defining the action of the burnishing-tool I have so employed the term more particularly with a view of distinguishing the action from the in-and-out movement of an indenting-tool or indenter.

55 Having thus described the invention, what

is claimed as new, and desired to be secured by Letters Patent, is—

1. In a machine of the character described, a burnishing-tool having an engaging surface formed to engage stitch impressions on the edges of shoe-soles, said engaging surface being rounded at a point adjacent the end of the tool to present a smooth corner to the impression being treated, and means for imparting repeated polishing movements to said tool while in uninterrupted contact with said impression. 70

2. In a machine of the character described, a burnishing-tool having an edge formed to engage stitch impressions on the edges of shoe-soles, said edge having a rounded end, and means for imparting a rapid longitudinally-reciprocating movement to said tool. 80

3. In a machine of the character described, a rotatable burnishing-tool having an edge formed to engage stitch impressions on the edges of shoe-soles, said edge having a rounded end, and means for imparting a rapid longitudinally-reciprocating movement to said tool. 85

4. In a machine of the character described, a burnishing-tool formed to engage stitch impressions on the edges of shoe-soles, and instrumentalities whereby said tool may simultaneously rotate and axially reciprocate. 90

5. In a machine of the character described, a tool comprising a rotatable wheel having a ribbed periphery, and means for rapidly reciprocating the same longitudinally of said peripheral ribs to impart to the same a burnishing action. 100

6. In a machine of the character described, a tool having a ribbed periphery and rounded end, and means whereby the same may reciprocate longitudinally of said peripheral ribs including a shaft on which the tool is rotatably mounted. 105

7. A fluted tool for burnishing stitch impressions having its flutes rounded at one end, and means whereby said tool may be reciprocated in a direction longitudinally of its flutes. 110

8. In a machine of the character described, a burnishing-tool formed to engage indentations arranged transversely at the edges of the stock, and means for imparting rapid polishing movements to said tool in a direction substantially lengthwise of the indentations. 115

9. A frusto-conical burnishing-tool for stitch impressions fluted on its tapered surface, and having the ends of its flutes at the larger end of the tool rounded, and means whereby said tool may be reciprocated in a direction longitudinally of its flutes. 125

10. A support, a fluted burnishing-tool free to revolve about the axis of its support, in combination with instrumentalities for axially reciprocating said tool. 130

11. In a machine of the character described, a burnishing - tool, a reciprocating shaft therefor, and means whereby the tool may rotate on said shaft, the axis of the tool being at an angle to the longitudinal axis of the shaft. justing the angle of said work-table, and means 65 for yieldably holding the tool toward the work-table, said tool being positioned at an angle to the line of reciprocation of its shaft.
12. In a machine of the character described, a burnishing-tool, a shaft for reciprocating the same, and means for mounting the tool on the shaft whereby the tool is bodily at an angle to the longitudinal axis of the shaft but with its operating-surface substantially parallel therewith. 19. In combination, a supporting-shaft, a tool formed for leather-working, loosely 70 mounted on said shaft whereby it is free to revolve about said shaft, and means including said shaft for rapidly reciprocating said tool axially to impart to the same a burnishing action. 75
13. In a machine of the character described, a burnishing-tool formed to engage imitation stitch impressions, means for imparting rapid polishing movements to the tool while in uninterrupted engagement with an impression whereby such impression may be finished prior to the treatment of a succeeding impression, and means for maintaining the engagement between said impression and tool during such polishing movements. 20. In a machine of the character described, a reciprocating shaft, a burnishing-tool pivotally supported on said shaft to turn in a direction transverse to the line of reciprocation of said shaft, means for reciprocating the shaft, a work-table, and means for adjusting the angular relation of the table and tool. 80
14. In a machine of the character described, a rotatable burnishing - tool formed to engage stitch impressions, on the edges of shoe-soles, means for axially reciprocating the same, and means for yieldably holding the tool in engagement with an impression whereby such impression may be finished prior to the treatment of a succeeding impression. 21. In a machine of the character described, a reciprocating shaft, a pivoted burnishing-tool operatively associated therewith to turn in a direction transverse to the line of reciprocation of the shaft, means for reciprocating the shaft, a work-table, and means for adjusting the angular relation of the table 85 and tool, said tool being positioned at an angle to the line of reciprocation of its shaft. 90
15. In a machine of the character described, a reciprocating shaft, a burnishing-tool free to revolve thereon, said tool being formed to engage stitch impressions on the edges of shoe-soles, a work-table, means tending to hold the tool toward the table, and means for moving the tool away from the tables against the action of said holding means, the line of reciprocation of the shaft being axially thereof. 22. In a machine of the character described, a reciprocating shaft, a burnishing-tool carried thereby having an edge disposed longitudinally of said shaft and formed to engage stitch impressions on the edges of shoe-soles, means for axially reciprocating the shaft, a work-table, and means for adjusting the angular relation of the table and tool. 95
16. In a machine of the character described, a rotatable burnishing-tool, formed to engage stitch impressions on the edges of shoe-soles, a reciprocating shaft carrying said tool, a work-table, means tending to maintain the tool and table in relatively close operative relation, and means for effecting a separation thereof, the line of reciprocation of the shaft being axially thereof. 23. In a machine of the character described, a reciprocating shaft, a burnishing-tool carried thereby having an edge disposed longitudinally of said shaft and formed to engage stitch impressions on the edges of shoe-soles, means whereby said tool may rotate, means for axially reciprocating the shaft, a work-table, and means for adjusting the angular relation of the table and tool. 100
17. A burnishing - tool, a reciprocating shaft on which the same is free to revolve in a direction transverse to the plane of reciprocation of said shaft, means for reciprocating the shaft, a work-table, and means for adjusting the angle of the table in relation to the tool. 24. In a machine of the character described, a reciprocating shaft, a burnishing-tool carried thereby having an edge disposed longitudinally of said shaft and formed to engage stitch impressions on the edges of shoe-soles, means whereby said tool may rotate, means for axially reciprocating the shaft, a work-table, and means for adjusting the angular relation of the table and tool, said tool being positioned bodily at an angle to the line of reciprocation of the shaft but with its operating edge substantially parallel therewith. 105
18. In a machine of the character described, a reciprocating shaft, a burnishing-tool pivotally supported on said shaft to turn in a direction transverse to the plane of reciprocation of said shaft, means for reciprocating the shaft, a work-table, means for ad-
19. In a machine of the character described, a burnishing-tool having a surface shaped to engage stitch impressions on the edges of shoe-soles, means for supporting said tool whereby the same may rotate, and 110

means for imparting a rapid polishing movement to said tool approximately lengthwise of its engaging surface.

26. A burnisher comprising a tool formed 5 to engage stitch impressions on the soles of shoes, and means for reciprocating said tool in a direction longitudinally of said impressions.

27. A burnisher comprising a tool formed 10 to engage imitation-stitch impressions on the soles of shoes, means for reciprocating said tool in a direction longitudinally of said impressions, and means permitting the tool to shift by progressive movements from engagement 15 with a burnished impression to the next adjoining unburnished impression.

28. In a machine of the character described, a rotatable burnishing-tool formed to engage stitch impressions on the edges of 20 shoe-soles, means for reciprocating the tool longitudinally of said impressions, and means for holding the tool in engagement with the work.

29. In a machine of the character described, a burnishing-tool formed for engagement 25 with stitch impressions on the edges of shoe-soles, means for imparting a rapid polishing movement to said tool longitudinally of said impressions, and means whereby the 30 tool is held in engagement with the work.

30. In a machine of the character described, a burnishing-tool formed to engage 35 stitch impressions on the edges of shoe-soles, means for imparting a rapid polishing movement to said tool, and means for holding the tool in operative engagement with each impression to permit complete burnishing thereof previous to the shifting of the tool to an adjoining impression.

40. 31. In combination with a tool formed for leather-working a shaft therefor, a rotatable operating-shaft, a cam on said last-mentioned shaft with which the end of the tool-shaft is arranged to engage to actuate the tool, means for normally preserving the contact therebetween, and means for destroying 45 said contact to prevent actuation of the tool including a shiftable member adapted to be interposed between said end of the tool-shaft 50 and the cam on the operating-shaft.

32. In combination with a tool formed for leather-working, a shaft therefor, a rotatable operating-shaft, a cam on said last-mentioned shaft with which the end of the tool-shaft is arranged to engage to actuate the tool, means for normally preserving the contact therebetween, and means for destroying 55 said contact to prevent actuation of the tool including a shiftable member sleeved on the 60 operating-shaft adapted to be interposed between said end of the tool-shaft and the cam on the operating-shaft.

33. In combination with a tool formed for leather-working a shaft therefor, a rotatable

operating-shaft, a cam on said last-mentioned shaft with which the end of the tool-shaft is arranged to engage to actuate the tool, said end comprising a part rounded in the direction of rotation of the operating-shaft, means for normally preserving the 70 contact between said end and the cam, and means for destroying said contact to prevent actuation of the tool including a rotatable member sleeved on the operating-shaft adapted to be interposed between the end of 75 the tool-shaft and the cam on the operating-shaft, said rotatable member having an open portion into which the end of the tool-shaft projects when the same is in engagement with the cam. 80

34. In combination with a tool formed for leather-working, a shaft therefor, a rotatable operating-shaft, a cam on said last-mentioned shaft with which the end of the tool-shaft is arranged to engage to actuate the 85 tool, said end comprising a roller mounted to rotate in the direction of rotation of the operating-shaft, means for normally preserving the contact between said roller and the cam, and means for destroying said contact to 90 prevent actuation of the tool including a rotatable member sleeved on the operating-shaft adapted to be interposed between the roller of the tool-shaft and the cam on the operating-shaft, said rotatable member having an open portion into which the roller of 95 the tool-shaft projects when the same is in engagement with the cam.

35. In combination with a ribbed tool formed for leather-working, means for imparting to said tool while in contact with the stock and without shifting the tool from its initial position of engagement with said stock a succession of rapid reciprocations in line with its rib. 105

36. In a machine of the character described, means for burnishing impressions on the edges of shoe-soles including a tool having a part formed to enter and engage a surface of an impression, and means for actuating said tool while uninterruptedly occupying a position within the same impression to cause the tool to repeatedly rub said surface. 110

37. In a machine of the character described, means for finishing and burnishing the walls of impressions on the edges of shoe-soles including a tool having a part formed to enter and engage a surface of an impression, and means for actuating said tool to impart 115 to the same repeated wiping actions over said surface of the impression. 120

38. A machine of the character described, having in combination, a work-support, an indenting-tool, means for vibrating the tool 125 while in contact with the work lengthwise of the indentations made by the tool, and means for adjusting the tool to change the angle of

movement of the tool with relation to the adjacent surface of the work-support, substantially as described.

39. A machine of the character described, having in combination, a work-support, an indenting-wheel mounted to rotate freely, and means for moving the wheel while in contact with the work lengthwise of the in-

dentations made by the wheel, substantially as described. ¹⁶

In testimony whereof I affix my signature in presence of two witnesses.

LOUIS W. G. FLYNT.
